RAIL CAR THRESHOLD CONSTRUCTION

Frederick L. Geary, Philadelphia, Pa., assignor
to Edward G. Budd Manufacturing Company,
Philadelphia, Pa., a corporation of Pennsyl-
vania

Application March 26, 1937, Serial No. 133,105

4 Claims. (Cl. 105—404)

The invention relates to rail car constructions and more particularly to the threshold construction of the doorway openings of baggage cars or the like.

5 It is an object of my invention to provide a construction in this region well adapted to take the heavy localized impact loads incident to the transferring of baggage or any heavy objects into or out of the car; to provide such a construction which will readily fit in with existing methods of assembly of the side frames and which will not add materially to the overall weight of the car, which in this instance, is 10 preferably of a light weight construction built 15 out of light gauge sheet metal of high tensile strength and adapted to be assembled by spot welding.

I attain these objects by strongly interbracing the threshold sill extended across the bottom of 20 the doorway opening with the bottom sill of the side frame, and I accomplish this in the form of the invention shown by a vertically deep beam structure extending across the threshold region and formed by interconnecting the threshold sill and bottom sill by a vertical plate extending 25 longitudinally through the thresholds and tying in this reinforced beam structure with the closely spaced floor beams whereby they mutually reinforce and interbrace each other.

30 Other and further objects and advantages and the manner in which they are obtained will become apparent from the following detailed description when read in connection with the appended drawing.

35 In the drawing:

Figure 1 represents a partial side elevation of the car body embodying the invention, parts of the outer sheathing or paneling being broken away.

40 Figure 2 is an enlarged fragmentary detailed view of the structure of Figure 1 at the bottom of a door post, with parts in front broken away to show parts in rear thereof.

45 Figure 3 is a cross sectional view on enlarged scale taken on the line 3—3 of Figure 1 looking in the direction of the arrows at the end of the section line.

50 Figure 4 is a cross sectional view taken along the line 4—4 of Figure 2 looking in the direction of the arrows at the end of the section line.

55 In the embodiment shown in the drawing, the side frame of the car is of the usual trussed construction embodying bottom and top chords and vertical and diagonal webs connecting the chords,

the parts being secured together through generous gussets located at the joints.

In the present embodiment the bottom chord of the truss comprises a Z-section bottom sill 10 on which are founded the vertically extending door posts 11 arranged at the opposite sides of the doorway opening, the door posts and the diagonals 12 extending upwardly from the bases of the door posts being secured to the bottom sill 10 by the generous gussets 13 overlapping the outer upwardly extending arm of the sill and the lower ends of the door posts and diagonals and secured thereto by spot welding.

As shown in Figure 4, the door posts comprise box-section structures built up out of flanged 15 channel members 14 closed by cover plates 15 spot welded to the flanges thereof and it is to these outwardly extending flanges that the gussets 13 are also spot welded.

In the assembly, the gussets are ordinarily 20 sub-assembled with the posts and this sub-assembly is then brought together in the final assembly with the other elements of the structure.

The floor 16 is arranged at a level some distance above the bottom sill 10 and supported at 25 the side by through running angles 17 which are in turn supported by channel stringers 18 resting on and secured to the transverse C-section floor beams 19. Ordinarily these floor beams overlap the sides of the posts and are directly 30 secured thereto. Since the door posts are widely spaced, the floor is reinforced in the doorway opening by two additional floor beams. These beams shown in Figure 1 are located between 35 the posts in the doorway opening and secured to the side frame in the manner to be subsequently described.

In the final assembly the threshold sill 20 running from post to post at the floor level and of 40 upwardly facing channel section is secured through its inner side wall to the vertically extending arm of the through running angles 17 as by spot welding. Its outer side wall is spot welded to a plate 21 of relatively thick gauge to enable it to take shear loads interconnecting it 45 with the bottom sill 10, the plate overlapping the vertically extending arm of the bottom sill and secured thereto by spot welding.

This vertical extending plate strongly reinforces and supports the threshold sill on the bottom sill and the ensemble produces in effect a 50 deep vertical beam which is capable of resisting the strong localized impacts to which it is subject in the loading or unloading of heavy pieces 55 of baggage or the like. The construction is such,

by reason of the openness of the joints, as to lend itself throughout to ease of assembly by spot welding.

The threshold sill may be further reinforced to make it in effect a box section structure by telescoping within it an inverted channel 22 and spot welding the side walls of the channels together. Access may be had for this spot welding operation through holes, one of which is indicated at 23, provided in the bottom of the channel 22. After the parts are so assembled, the bottom flanged channel moulding strip 24 and the corrugated outer sheathing 25 are applied in the usual manner. The bottom moulding strip 24 is a through running strip and adds further to the strength of the bottom chord of the side wall truss and the beam structure extending through the threshold.

It may be pointed out that the reinforcing plate interconnecting the top and bottom threshold sill 20 and the bottom sill 10 is shown in the instant construction as consisting of a separate plate 21 shorter than the width of the door opening, this plate being extended through the threshold by the projecting ends 26 of the gussets 13. The ends of the plate are strongly secured to the projecting portions 26 of the gussets by a plate 27 overlapping both these members and strongly secured thereto by spot welding. This joint forms the gussets and the separate plate 21, in effect, a continuous plate extending through and beyond the threshold. It will be understood that the extensions 26 of the gussets 13 are connected to the outer side wall 30 of the threshold sill 20 and to the upwardly extending arm of the sill 10 in the same manner as the plate 21. It will be understood that under some conditions of manufacture, it may be desirable to form the gussets 13 and plate 21 all out of one piece.

The floor beams 19 in the doorway opening rest upon the side sill 10 and are strongly secured to the vertical plate 21 by angle gussets 28 spot welded through one arm to a floor beam and through the other, to the plate 21. Thus the vertically deep floor beams and the vertically deep beam structure formed by the sill 10, plate 21 and threshold sill 20 and extending through the threshold mutually reinforce and interbrace each other, the beam extending through the threshold providing a strong anchorage for the ends of the floor beams and the floor beams stabilizing the plate 21 against buckling under the heavy impact loads to which it is subject.

While I have herein described a preferred form of carrying out my invention, it will be understood that changes and modifications may be made by those skilled in the art which still fall within the scope of the invention as set forth in the appended claims.

What I claim is:

1. In a rail car construction, a through-running longitudinally straight bottom side sill arranged some distance below the floor level, a longitudinal floor supporting member, vertical posts founded on said sill and rising on the opposite sides of a doorway opening, said longitudinal member being secured to the inside faces of the posts a threshold sill of hollow cross section secured through one side thereof to the longitudinal member and through its other side wall to a vertical extension of the side sill.

2. In a rail car construction, a side sill, posts rising from said side sill at opposite sides of a doorway opening, a threshold sill member of vertically presenting channel section extending between said posts with the vertical sides of the channel substantially in the planes of the outer and inner faces of the posts, and means supporting said threshold sill through its outside vertical side wall from the side sill and through its inside vertical side wall from a through running floor stringer secured to the inside of the posts.

3. In a rail car construction, a through-running longitudinally straight side sill, door posts rising therefrom at opposite sides of a doorway opening and secured directly thereto, a threshold sill, a deep vertical plate interconnecting said side and threshold sills and forming therewith a vertically deep beam extending through the threshold, said plate overlapping and being rigidly secured to the door posts, and a vertically deep floor beam having its end secured rigidly throughout a substantial part of the vertical extent of said vertically deep beam whereby to stabilize the same.

4. In a rail car construction, a bottom sill, a sill some distance above said bottom sill and at substantially the level of the floor of the car, posts at opposite sides of a doorway opening founded on one of said sills, a vertically deep plate interconnecting the sills and forming therewith a deep beam extending through the threshold, and a vertically deep floor beam between the posts having its end rigidly connected to the plate throughout a substantial part of its vertical extent whereby to stabilize the same.

FREDERICK L. GEARY.
